VACUUM BREAK DEVICE FOR WATER SERVICE SYSTEMS

Joseph A. Vogel, Wilmington, Del., assignor to
 Joseph A. Vogel Company, Wilmington, Del., a
 corporation of Delaware

Application March 26, 1934, Serial No. 717,492

3 Claims. (Cl. 4—70)

This application is a continuation in part of my prior application, Serial No. 678,046, filed June 28, 1933.

This invention relates to improvements in water closet and other similar water supply systems, and particularly to systems of that kind embodying a bowl or other suitable receptacle having fresh water supply and waste outlet connections; and the main object of the invention is to provide simple, reliable and efficient means for preventing siphonage of any waste from the bowl or receptacle to the water supply line, and the contamination of the water in the latter by impurities, in the event that the bowl or receptacle should become filled and overflowing.

A further object of the invention is to provide a vacuum break device and drain channel for the above specified purpose which will also serve as conducting means for returning to the bowl any waste matter which may enter said device.

In the present instance, for the purpose of enabling my invention to be fully understood, I have shown my invention as applied for use to a water closet system of frost-proof type, such as a Vogel frost-proof water closet system, although it is to be understood that it may be embodied in other types of water closet systems and to water distribution apparatus generally, to drinking fountains, wash sinks, hydrants, and other water service apparatus having a receiving bowl or other receptacle provided with water supply and waste outlet connections.

In order that my invention may be fully understood in all its aspects I have herein shown the same in the accompanying drawings as applied, for example, to the closet apparatus disclosed in my aforesaid application Serial No. 678,046, in which drawings:

Fig. 1 is a side elevation showing the application of the invention to a Vogel type of frost-proof water closet.

Fig. 2 is a vertical front-to-rear section through the water supply and drain valve mechanism thereof on an enlarged scale and showing the application of the invention thereto.

Fig. 3 is a view in rear elevation of the upper portion of the standpipe and showing more particularly the arrangement of the siphon device.

Fig. 4 is a vertical transverse section through the lower portion of the standpipe on a further enlarged scale and more clearly showing certain features of construction.

Fig. 5 is a fragmentary cross section through the rear portion of the bowl and showing the

vacuum relief or break device and drain channel associated therewith.

Fig. 6 is a section similar to Fig. 2.

Figs. 7 to 10, inclusive, are cross sections similar to Fig. 5, showing modified forms of the invention.

Referring now more particularly to the drawings, 1 designates a closet bowl provided at its upper rear portion with an inlet 2 for supply of flush water thereto and having an outlet 3 at its base for connection, in the usual manner, with a waste pipe and trap 3' communicating with the bowl chamber 1a and forming part of a waste disposal or sewage system. In practice the trap is designed to be arranged below the frost line, 10 in the use of the closet in exposed places, in order to prevent liability of the freezing of water therein.

Disposed adjacent the top of the bowl and in rear thereof is a valve casing 4 formed with an upper flush chamber 5, a flush discharge outlet 6, and a lower flush chamber or passage 7 having a lateral inflow and outflow connection 8. The flush discharge outlet 6 communicates with the inlet 2 of the bowl while the connection 8 is provided for communication with the water supply tank 9. Extending downwardly from the lower end of the casing is a standpipe or conductor 10 having a water inlet 11 at its lower end for connection with a water service or supply pipe 12 and having a drain outlet 13 above the level of the water inlet 11, for a purpose hereinafter described.

Arranged within the valve casing 5 and the standpipe 10 is a valve stem 14 carrying within the chamber 7 an upper flushing valve 15 movable to alternately open and close communication between the chambers 5 and 7. At its lower end the valve stem carries a valve 16 controlling the water supply inlet 11, and a valve 17 controlling the drain outlet 13, the drain valve being hollow and portions of the valve stem above and below the plane of said drain valve 17 being of openwork construction or provided with ports 18 and 19 to allow water to flow between the pipe 10 above the level of the drain valve and the drain outlet 13 or water inlet 11 in the different positions of the valve members 16 and 17. A spring 20 associated with the upper end of the valve acts, in conjunction with gravity, to maintain the valve device in a position in which valve 16 closes inlet 11, valve 17 is open and connects that part of the pipe 10 above the drain valve with the drain outlet 13, and the valve member 15 is open so that chambers 5 and 7 and the closet and tank are in open com- 50

munication. A forked arm 21 carried by the pivotally mounted closet seat 22 engages under a head 23 fixed to the upper projecting end of the valve stem and operates thereon to lift the valve 15 when the seat is depressed. On depression of the seat the valve stem is raised to close valve 15 and cut off communication between the pipe 10 and the bowl and to move valve 17 to a position in which it closes the drain pipe 13 and simultaneously moves valve 16 to open position, for the upflow of water through the connection 8 from the supply pipe 12 to the tank 9. The tank will thereupon be filled with water and the air therein compressed until the pressure equals or exceeds that in the supply line, at which the flow of water will be automatically cut off. When the seat 22 is released spring 20 moves the valve stem downward to close the valve 16 and to open the valve 15 to establish communication between the tank and bowl for the flushing action and to simultaneously open communication between the lower end of the pipe 11 and the drain outlet 15 for the subsequent drainage off of residual water remaining in the flushing connection at the end of the flushing action, as hereinafter described.

A siphonage device 24 is provided for the purpose of effecting a rapid siphonage off from the standpipe and parts of the flushing system above the inlet valve of any and all water remaining in the flushing system, in order to avoid any possibility of the freezing or contamination thereof. This siphonage device comprises a looped tube having a short limb 25 and a long limb 26 connected at their upper ends by a return portion 27. The limbs or legs 25 and 26 are arranged in parallel relation to the pipe 10 and the return portion is preferably disposed so as to loop about the connection 8 and to lie at a level above the highest level of the bowl. The short limb 25 extends downwardly from the return portion 27 and communicates at its lower end with the standpipe 10 through a passage 28, at about the level of the drain outlet 13, so that in the closed position of valve 17 both passages 13 and 28 will be closed while in the open position of said valve 17 both of said passages 13 and 28 will be open. The longer or outlet leg 26 of the siphon extends downwardly to a point below the level of the lower end of leg 25 for the discharge of the siphon water therefrom into the ground outside the standpipe or into a suitable outlet connection. The leg 26 is made of such length relative to the leg 25 as to ensure an efficient siphonage action and in practice this leg 26 may be made of fluted or zig-zag form or otherwise offset or shaped to increase its effective length to a degree greater than the distance between its upper and lower ends in order to further quicken and increase the efficiency of the siphonage action.

In its operation, the siphonage device 24, which may be made of copper tubing of suitable gage, is primed for action by the upflow of water through its leg 25 into its leg 26 during the flushing action, so that, upon the closing of the valve 16, and cessation of the flushing action, the water remaining trapped in the pipe 10 will be immediately siphoned off through the siphonage device, in order that a sufficient amount of water is present for the siphonage action, whereby the standpipe and its connections above the water supply valve 15 will be freed from water liable to freeze or to be contaminated. By this means all liability of freezing of pipes or derangement of parts of the flushing apparatus due to freezing during cold weather, particularly when the parts of the flushing apparatus above the inlet valve are arranged

above the frost line, will be prevented in a certain, reliable and efficient manner at all times whenever there is a sufficient amount of residual water present to operate the siphonage discharge device. By this means, also, the flushing apparatus, when not in use, will be kept clear of any water liable to be fouled by sewage or other contamination.

The drainage connection 13 is provided in order to ensure discharge of any residual water from the standpipe in the event that the amount of water remaining is not sufficient to cause a siphonage action. This outlet 13 communicates through a pipe 29 terminating in an open valve cage 30 in which is arranged a ball valve 31. This valve opens automatically to permit of a drainage action and then closes to seal the drainage connection 13 against the admission of air, water or other foreign substances. This valve 31 operates to close the outlet 13 at all times and particularly when said outlet is not closed by the valve 17, the valve 31 being of such size and weight as to open readily under the pressure of a comparatively small amount of water in the standpipe to effect the discharge of the water. The parts 30 and 31 are in practice preferably covered by a suitable hood 32 in order to shield the same from obstruction or entrance by foreign particles.

In accordance with my present invention, and as disclosed particularly in connection with the structure shown in Figs. 1 to 5, inclusive, I provide an air intake or vacuum-break device 33 to break the vacuum and prevent siphonage in the event that the bowl should become filled and overflowing. This air intake or vacuum-break device comprises a tube or pipe 34 having one end 35 disposed in the bowl intake passage in connection 6 and the tube thence extends outwardly and is bent or looped around part 6 and has its opposite end 36 located at one side of part 6 and terminating immediately above or within and in spaced relation to the upper inlet end of a drain channel or vent passage 37. This channel or passage 37 is formed in the part 2 of the bowl with its upper end opening through the rim of the bowl and its lower end communicating with the top of the body of the bowl below the base of the rim, through which channel or passage 36 any fluid entering said tube or pipe 34 and discharged through end 35 may be caught and conducted back into the bowl instead of discharging upon the exterior thereof. By the use of this air intake or vacuum break device a simple, reliable and effective type of means is provided for preventing siphonage of any waste from the bowl or receptacle to the water supply line and the contamination of the water therein by waste impurities, in the event that the bowl or receptacle should become filled and overflowing. A similar advantage may be obtained in the use of the device in other like water service systems.

The use of the channel or passage 37 may not be necessary where conditions are such that no leakage can or is liable to take place through the air break tube. It is, however, preferably provided to take care of any leakage under conditions where leakage may or is liable to occur, as, for example, when used in connection with valves of the flushometer type. It will be understood, of course, that while the channel 37 will preferably be formed in or upon a bowl in a water closet combination or like service system, any equivalent thereof may be employed, and the channel may be constructed and arranged to

conduct the leakage into any waste receptacle or waste part of the service system.

Many and various modifications in the construction of the air break means herein disclosed may be employed, some of which are shown. In Fig. 6, for example, a slightly modified form of air break tube 33a is used in connection with a slightly modified form of flush connection 6a, but in which the ends 35a and 36a of the tube 10 are arranged for cooperation with said connection and the drain channel 37a as in the construction previously described. In Fig. 7 a U-shaped form of tube 33b is employed which extends through one side of another modified form 15 of flush connection 6b with its inner and outer ends 35b and 36b communicating respectively with the flush channel and overlying the drain channel 37b. In Fig. 8 an air break tube 33c, similar to the tube 33b extends through one side 20 of a flush connection 6c with its inner and outer ends 35c and 36c communicating respectively with the flush channel and overlying an opening in a flange of the flush connection 6c, which opening is in alignment with the drain channel 37c. In Fig. 9 an air break tube 33d, similar 25 to tubes 33b and 33c, extends through one side of the flush connection 6d with its inner end 36d arranged within the flush channel and its outer end 35d fitting within a nipple 39 communicating 30 with the drain channel 37d and molded as an integral part on the bowl structure. In Fig. 10 an air break tube 33e of U-form extends through one side of a flanged flush connection 6e with its inner end 36e disposed in the flush channel 35 and its outer end arranged above an opening in the connection flange 40, which opening registers with a drain channel 37e which communicates with the water intake or flush channel 2 in the bowl. Obviously other and equivalent ways 40 of carrying the invention into practical effect may be employed, varied in form and arrangement to suit the particular kind of closet flush or water service fixture in connection with which the invention is to be used. I, therefore, do not 45 limit myself in these particulars, as such modifications and other modifications falling within the scope of the appended claims may be made without departing from the spirit or sacrificing any of the advantages of the invention.

What I claim is:—

1. In a water service apparatus, a bowl having a main chamber with a discharge connection at its bottom, a water supply passage at its top and a drain channel leading from the top of the bowl 55 from a point at one side of the inlet of the supply passage and thence downwardly into the bowl

without communicating with said passage but communicating with the water chamber below the level of the top of said chamber, a water supply conductor communicating with the inlet of the water supply passage, and a vacuum break conductor extending through the water supply conductor and communicating at its inner end with said conductor and at its outer end with the external atmosphere, the latter-named end of said vacuum break conductor being disposed in spaced 10 but conducting relation to the upper end of the drain channel.

2. In a water service apparatus, a bowl having a main chamber with a discharge connection at its bottom, a water supply passage at its top and a drain channel leading from the top of the bowl 15 from a point at one side of the inlet of the supply passage and thence downwardly into the bowl without communicating with said passage but communicating with the water chamber below the level of the top of said chamber, the bowl having an upstanding tubular projection communicating with the top of said channel, a water supply conductor communicating with the inlet of the water supply passage, and a vacuum break conductor 20 extending through the water supply conductor and communicating at its inner end with said conductor and at its outer end with the external atmosphere, the latter-named end of said vacuum break conductor depending into said tubular 25 projection in spaced relation thereto.

3. In a water service apparatus, a bowl having a main chamber with a discharge connection at its bottom, a water supply passage at its top and a drain channel leading from the top of the bowl 35 from a point at one side of the inlet of the supply passage and thence downwardly into the bowl without communicating with said passage but communicating with the water chamber below the level of the top of said chamber, a water supply conductor having a portion provided with a water discharge passage communicating with the discharge passage of the bowl and provided with a lateral projection resting on the bowl and formed with a port communicating with the upper end of the drain channel, and a vacuum break conductor 40 extending through the water supply conductor and communicating at its inner end with said conductor and at its outer end with the external atmosphere, the latter-named end of said vacuum break conductor being of smaller diameter than the port in said lateral projection and arranged immediately thereabove for the drain of water 45 therefrom into said channel.

JOSEPH A. VOGEL.
